UNITED STATES PATENT OFFICE.

ERNEST A. OETZEN, OF EVERETT, WASHINGTON, ASSIGNOR TO SUMNER IRON WORKS,
OF EVERETT, WASHINGTON, A CORPORATION OF WASHINGTON.

LUMBER CARRIER.

Application filed April 3, 1926. Serial No. 99,588.

My invention relates to lumber carriers and other types of straddling hoists. The object of my invention is to provide a device of this character, with its hoisting mechanism in such a manner that the power devices can be collected compactly at the middle of the frame and act thru a series of fulcrumed levers to lift the load engaging elements at each corner of the frame.

10 I attain this object by mounting on a straddling frame, a motor, and arrange the power transmission devices directly connected with said motor across the transverse middle of the frame and down the middle 15 of each of the leg portions. I connect the load engaging shoes at the corners of said frame to said power transmission devices at that side thru fulcrumed levers. In this manner it is necessary to provide but two 20 sets of power transmitting devices from the motor to serve four load engaging elements.

In all lumber carriers with which I am familiar, it has been considered necessary to provide separate hoisting means at each corner and to connect each of said hoisting means separately to the motor. By my invention, therefore, I am able to save one-half of the power transmitting devices and thus not only eliminate their cost, but also 30 eliminate the play which would otherwise be permitted by the connections of their various elements.

A further object of my invention is to provide power transmitting devices in which 35 all of the elements are relatively stiff members and thus eliminate the frequent breakdowns caused by breakage of chain, cables, and the like.

A further and incidental object of my invention is to introduce a certain measure of 40 resiliency in said latter stiff connections to prevent a blow given to the load carried by said carrier from being transmitted with undiminished force to the hoisting mechanism. To attain this later object, I proportion 45 the connections at either or both ends of the fulcrumed levers so that there is a substantial play in said connections and thus if said load engaging shoes strike a projection, the blow thus given said shoe will not

be transmitted directly to said hoisting mechanism because of the play thus provided, and thus said connections will not be strained.

Further devices for cushioning said connections are spring elements in said power transmission devices, which springs are arranged so that they do not carry any of the load, but permit the fulcrumed levers to be rotated by a jar or blow if the play provided is insufficient. In other words, the spring elements provided in said power transmitting devices supplement the play provided in said connections to permit the movement of said shoes upwardly upon striking a projection without injuring the power transmitting devices or the hoisting mechanism.

Further details of construction and the mode of operation are hereinafter described with reference to the accompanying drawings, in which:

Fig. 1 is a perspective view of a lumber carrier, embodying my invention;

Fig. 2 is a plan view thereof with the seat and other auxiliary devices removed 75 from the top of the frame to disclose details of construction, which would otherwise be concealed;

Fig. 3 is a vertical section taken on the line 3—3 of Fig. 2 showing the hoisting devices at one side of said lumber carrier in elevated position;

Fig. 4 is an enlarged fragmentary elevation of said hoisting devices as viewed in Fig. 3;

Fig. 5 is a similar scaled section taken on the line 5—5 of Fig. 4;

Fig. 6 is a similar scaled section taken on the line 6—6 of Fig. 4 thru the load engaging element at one end on said straddling legs.

Fig. 7 is a similar section taken on the line 7—7 of Fig. 4 showing one load engaging element, the load engaging flange carried thereby and also the guides for said load engaging element;

Fig. 8 is a still larger scaled section of the inner end of one of said fulcrumed levers illustrating how a separate wearing plate 100 can be provided;

- Fig. 9 is a section of said end taken on the line 9—9 of Fig. 8;
- Fig. 10 is a transverse section taken on the line 10—10 of Fig. 3;
- 5 Fig. 11 is a section taken on the line 11—11 of Fig. 3 except on a larger scale, showing the power transmitting means at one side of the lumber carrier;
- Fig. 12 is a fragmentary elevation showing a modified embodiment of my invention in which the power transmitting devices include a pulley-and-cable element;
- 10 Fig. 13 is a plan view of the modification shown in Fig. 12;
- 15 Fig. 14 is a section taken on the line 14—14 of Fig. 12;
- Fig. 15 is a fragmentary elevation of a still further modification of my invention in which the power transmitting devices embody a piston-and-cylinder element, said elevation being taken substantially on the line 15—15 of Fig. 16;
- 20 Fig. 16 is a plan view of said latter modification; and
- 25 Fig. 17 is a transverse section thereof taken substantially on the line 17—17 of Fig. 15.
- My improved lumber carrier comprises a frame having dependent sides 1^a and 1^b spaced apart laterally and defining a load carrying space 1^c between them. Said frame is mounted on wheels 2 carried by spindles 3, the front spindles being guidable by steering mechanism comprising arms 4^a connected together by a rod 4^b and connected to the steering wheel 4^c and by a rod 4^d, in the usual manner.
- 30 Each of said side portions comprise horizontal channel or I-beam members 1^d which are spaced apart and carried by end members 1^e. At the center of each side frame two vertically arranged structural members 1^f are provided spaced apart and defining a guideway between them, and in said guideway a block 5 is mounted for reciprocation in said guideway, and held by said structural members 1^f at each side thereof.
- 35 Between said structural members 1^f and the end members 1^e are located, at each side, trunnions 6, said trunnions being carried by the lowermost side member 1^d being fastened thereto by bolts 6^a.
- 40 Extending inwardly from said trunnions 6 are centrally arranged stub-shafts 6^b. Said trunnion is provided with an upstanding web portion 6^c and to said web portion I connect divergent structural members 1^g which connect to the uppermost side member 1^d as shown clearly in Fig. 3. Said structural members 1^g thus tie each trunnion 6 to the uppermost frame member 1^d so that the said trunnions are connected to said upper member as well as to the lowermost one upon which it is seated. Said structural members diverge towards said upper mem-
- ber and thus spread the load, carried by the trunnion, as will later be pointed out, along the entire length of said uppermost side member 1^d.
- Pivotedly carried upon each of the stub-shafts 6^b, is a fulcrumed lever 7 which connects the blocks 5 at each side with the load engaging members 8 at each end of said sides.
- 70 The ends of said 7^a and 7^b of said fulcrumed levers 7 are preferably formed into circular knobs, the ends 7^a engaging a boxing 8^a formed in each of said load engaging members 8 and the ends 7^b of the fulcrumed levers, at each side of said frame, engaging 80 boxings 5^a in the slidable block at that side of said frame.
- 75 Said circular ends 7^a and 7^b respectively are preferably provided with wearing plates 7^c and 7^d, respectively, made of harder material but conforming to the outline of said ends 7^a and 7^b respectively and being fastened thereto by stud-like pins 12. A wearing plate made of harder material thus minimizes the wear upon said circular ends 80 without increasing the cost thereof a substantial amount.
- 85 Said load engaging members 8 are mounted for vertical reciprocal movement in said side portions, and the load engaging members at each side carry a slightly flexible load engaging flange 9 between them, said load engaging flange being fastened to each by a stud 10.
- 90 The guides 11 for said load engaging members are relatively short and shoulders 8^b are formed on said load engaging members, arranged to engage said guides in the lowermost position of said engaging members, thereby to support said engaging members, in said position upon said guides 11.
- 95 Said blocks 5 are of substantial length exceeding the width of said boxings by a substantial degree and the remainder of the length of said blocks is formed into guides 5^b which are connected by a plate-like web 5^c. Formed upon said block 5 are two spaced ears 5^d and pivotally mounted between said ears on a pin 13 is a tongue 14^a which is an integral portion of a box 14 as 100 shown clearly in Figs. 4 and 11.
- 105 Said blocks 5 are of substantial length exceeding the width of said boxings by a substantial degree and the remainder of the length of said blocks is formed into guides 5^b which are connected by a plate-like web 5^c. Formed upon said block 5 are two spaced ears 5^d and pivotally mounted between said ears on a pin 13 is a tongue 14^a which is an integral portion of a box 14 as 110 shown clearly in Figs. 4 and 11.
- 110 Said blocks 5 are of substantial length exceeding the width of said boxings by a substantial degree and the remainder of the length of said blocks is formed into guides 5^b which are connected by a plate-like web 5^c. Formed upon said block 5 are two spaced ears 5^d and pivotally mounted between said ears on a pin 13 is a tongue 14^a which is an integral portion of a box 14 as 115 shown clearly in Figs. 4 and 11.
- 115 A threaded lifting rod 15 is connected to said box thru spring elements 16 carried on guide pins 17 in said box. Said threaded rod 15 terminates in a T-head 15^a, which is provided with apertures thru which said guide pins 16 extend and thus said pins act not only as keepers for the springs 16 but also as guides for said rod 15, when the latter tends to twist in said box 14 and the rod 15 is journaled at its upper end in a casing 18 carried by the uppermost side member 1^d.
- 120 Keyed to said threaded rod is a bevel gear 19 which meshes with a similar gear 20 125
- 125

keyed to the stub-shaft 21 also journaled in said casing 18. Fixed to said stub-shaft 21 is a sprocket 22 which is connected to a sprocket 23 on the transverse shaft 24, by a chain 25.

Similar lifting mechanism is provided at the opposite side of said lumber carrier and operates similar hoisting mechanism at that side, both of said power transmission devices 10 being connected to the main shaft 24, which is in two halves, each half being rotated in opposite directions thru ordinary reverse gearing 24^a.

The said reverse gearing is connected to 15 the motor 26 thru a power take-off shaft 27, and the main propelling shaft 28 is used for driving the vehicle thru a rear driving shaft 29 and chains 30, in the common manner.

Said reverse gearing is controlled by a 20 hand lever 31 adjacent the driver's seat. Said hand lever is connected to a pivoted control rod 32 thru a link 33 and thus when the lever 31 is pulled in one direction it will move the reverse gear so as to lift the load, 25 and when moved in the opposite direction will reverse said hoisting mechanism and permit said load to be lowered.

Especial attention is called to the connection of the fulcrumed levers with the block 30 5 and with the load engaging devices 8 respectively, such connections being shown clearly in Fig. 4. The boxings 5^a and 8^a respectively, in said block and said load engaging elements are substantially wider than the diameter of said circular ends 7^b and 7^a, 35 respectively. Thus, there is considerable play between said circular ends and their boxings. As is evident, the said boxings will ride upon said circular ends in the manner shown in Fig. 4 under ordinary circumstances. If, however, one end of either of the load engaging flanges 9 strikes a projection, the blow to which all of the hoisting mechanism would be subjected, is eliminated, because of said play, which play permits the load engaging elements 8 and the 45 levers 7 to move slightly without affecting the power transmission devices.

Furthermore this play provides for the 50 slight elongation of the levers 7 as they approach a horizontal position on their fulcrums.

As an added precaution to prevent injury to said power transmission devices, I provide the springs 16 previously noted. Thus, if the load engaging element 8 shown in Fig. 4 was driven upwardly by a blow, it would rock the lever 7 counter-clockwise about the stub-shaft 6^b and would cause the 60 circular ends 7^a and 7^b, respectively, to take up the play in their boxings 5^a and 8^a, respectively. If the blow tends to cause said parts to move further, the engagement of said block 5 thru the boxing 5^a would be 65 pulled downwardly in its guides 1^t, and the

springs 16 supporting said boxing would be compressed slightly. The amount of play between said circular ends and their boxings, however, is proportioned to take care of all ordinary jars because said block 5 70 will be held, to a certain degree, in position by the end 7^b of the opposite lever, if only one of said levers is rocked.

In Figs. 12 to 14 inclusive, I show my invention embodied in a lumber carrier in 75 which the power transmitting devices comprise a drum-and-cable lift. In all other respects, however, the parts are the same as the former modification, and thus will not be described in detail, but will be referred 80 to by the same reference characters given said parts in the modification shown in Figs. 1 to 11, inclusive.

The fulcrumed levers 7 are connected by the sliding block 34 which is carried by the 85 lower end of a post-like slide 35, arranged for vertical reciprocation in the frame of said lumber carrier between the guiding flanges 1^t. Carried by each of said post-like slides 35 are one or more rotatably 90 mounted sheaves 36, two being shown in Fig. 12, for convenience. A cable drum 37 is carried by each end, of the transverse driving shaft 24^b carrying reversing mechanism 24^c and a cable 38 is wound about the 95 periphery of each of said cable drums 37, and is passed under a fixed guide pulley 39 rotatably carried by the frame adjacent said post-like slide. From there the cable is lead over said guide sheaves 36 carried by 100 said slide 35, and the end of said cable is anchored to the frame upon a pin 40 at the opposite side of each of said post-like slides 35.

To lift a load of lumber, it is necessary 105 that the load engaging elements 8 be moved upwardly, and thus the fulcrumed levers 7 must be rocked to lift each of the ends 7^a thereof and lower the ends 7^b. To lower the ends 7^b, the post-like slide 35 must be 110 lowered correspondingly.

The mass of said post-like slides is considerably less than that of the load engaging elements 8 and thus said load engaging elements, even when disengaged from a load 115 will tend to move said box-like slides upwardly. Therefore, when a load is carried by said elements 8, the force tending to move said slides upwardly is correspondingly increased.

It is not necessary, therefore, to provide means for moving said posts upwardly and the cable 38 is mounted over the various sheaves to lower said posts when the cable is tightened, and said post is permitted to move 125 upwardly when said cable is slackened.

In this modification, it is not necessary to provide a spring-like element similar to the elements 14, 16, and 17 in the previously described modification because said slide is 130

free to be moved downwardly because of the absence of stiff holding means tending to move the same upwardly.

In Figs. 15 to 17 inclusive, I show a still further modification of a lumber carrier embodying my invention. In this latter modification, power transmitting means comprising a piston-and-cylinder element is provided to reciprocate the slidable block 5 vertically in its guides 1⁶.

The rods 41 shown in Figs. 15 to 17, inclusive, are the piston rods depending from the piston-and-cylinder elements 42 carried upon the upper portion of the frame 1. Said pistons are reciprocated to and fro in said cylinders by fluid compressed by a pump element shown diagrammatically as 43, which pump element is driven by a motor indicated diagrammatically as 44.

Each cylinder is controlled by a separate valve 45 which not only controls the flow of fluid to said piston, but also the flow from the latter, said piston-and-cylinder element being double acting. A fluid supply pipe 46 is branched and connects from said pump 43 to both of the valves 45, and a discharge pipe 47 is similarly connected to said valves and said pump. A rod 48 connects the actuating levers 49 on each of said valves, which actuating levers are arranged to be actuated similarly when the rod 48 is moved in one direction.

Thus, for example, the valves are arranged to supply fluid to the cylinders 42, to actuate the same and to lift the load carrying elements when said rod is moved towards the left in Fig. 17. When the rod is reversely moved, said valves are arranged to actuate said piston-and-cylinder elements 40 to drive the pistons in the opposite direction to lower the load engaging elements.

In this modification, I show the elements 14, 16, and 17 also shown in the modification in Figs. 1 to 11, inclusive, for the reason that even tho a compressible fluid is used, the pressures in said cylinders will be so intense that very little relative elasticity will be provided thereby.

I claim:

1. A lumber carrier of the character described, comprising a load straddling frame, vertically slidable load engaging elements carried by the corners of said frame, fulcrumed levers engaged at one end to said load carrying elements respectively, vertically movable, centrally located power transmitting element with which the other ends of said levers are connected, a motor and connections therefor to said power transmitting element, including a yielding element for the purpose described.

2. A lumber carrier of the character described, comprising a load straddling frame, vertically slidable load engaging elements

carried by the corners of said frame, fulcrumed levers engaged at one end to said load carrying elements respectively, vertically movable, centrally located power transmitting element with which the other ends of said levers are connected, a motor and connections therefor to said power transmitting element, said power transmitting element comprising blocks at each side of said frame vertically slidable therein and constituting the connecting means of said power transmitting element with said fulcrumed levers, and said block including a yielding element for the purpose described.

3. In a lumber carrier of the character described, a load straddling frame having laterally spaced dependent side portions, said side portions comprising two longitudinally arranged members spaced apart a substantial distance, a motor carried by said frame, power transmission means operatively connected to said motor, vertically slidable load carrying elements carried by the corners of said frame, fulcrumed levers engaged at one end with said load carrying elements, respectively, pivots for said levers carried by one of said longitudinal members, divergent frame members connecting each pivot to the other of said longitudinal members, and the other ends of said fulcrumed levers being connected to said power transmission means.

4. In a lumber carrier of the character described, a load straddling frame having laterally spaced dependent side portions, a motor carried by said frame, power transmission means operatively connected to said motor, vertically slidable load carrying elements carried by the corners of said frame, said frame and said elements having mutually formed engaging shoulders abutting when said load engaging elements move to lowered or load engaging position, fulcrumed levers engaged at one end with said load carrying elements, respectively, the other ends of said fulcrumed levers being connected to said power transmission means.

5. In a lumber carrier of the character described, a load straddling frame having laterally spaced dependent side portions, a motor carried by said frame, power transmission means operatively connected to said motor, vertically slidable load carrying elements carried by the corners of said frame, means carried by each of said load engaging elements and said frame, respectively, for limiting the movement of said load engaging elements in said frame in one direction, fulcrumed levers engaged at one end with said load carrying elements, respectively, and the other ends of said fulcrumed levers being connected to said power transmission means.

6. In a lumber carrier of the character described, a load straddling frame having

laterally spaced dependent side portions, a motor carried by said frame, power transmission means operatively connected to said motor, vertically slidable load carrying elements carried by the corners of said frame, said power transmission means comprising a block vertically slidable in each of said side portions, and a vertically mounted threaded screw connected therewith, fulcrumed levers engaged at one end with said load carrying elements, respectively, and the other ends of said fulcrumed levers being connected to said blocks.

7. In a lumber carrier of the character described, a load straddling frame having laterally spaced dependent side portions, a motor carried by said frame, power transmission means operatively connected to said motor, vertically slidable load carrying elements carried by the corners of said frame, said power transmission means comprising a block vertically slidable in each of said side portions, and a vertically mounted threaded screw connected therewith, fulcrumed levers engaged at one end with said load carrying elements, respectively, the other ends of said fulcrumed levers being connected to said blocks, and the end of each of said screw engaged by said blocks, respectively, terminating in a T-shaped head, said block carrying a box, and a spring element spacing the T-shaped end of said screw from said box.

8. In a lumber carrier of the character described, a load straddling frame having laterally spaced dependent side portions, a motor carried by said frame, power transmission means operatively connected to said motor, vertically slidable load carrying elements carried by the corners of said frame, said power transmission means comprising a block vertically slidable in each of said side portions, and a vertically mounted threaded screw connected therewith, fulcrumed levers engaged at one end with said load carrying elements, respectively, the other ends of said fulcrumed levers being connected to said blocks, the end of each of said screw engaged by said blocks, respectively, terminating in a T-shaped head, said block carrying a box, and a spring element spacing the T-shaped end of said screw from said box, and guide pins in said box, the

end of said threaded rod being slidably mounted on the latter.

9. In a lumber carrier of the character described, a load straddling frame having laterally spaced dependent side portions, a motor carried by said frame, power transmission means operatively connected to said motor, vertically slidable load carrying elements carried by the corners of said frame, fulcrumed levers engaged at one end with said load carrying elements, respectively, the other ends of said fulcrumed levers being connected to said power transmission means, said levers terminating in circular knobs, and said load engaging elements and said block provided with boxings engaged thereby.

10. In a lumber carrier of the character described, a load straddling frame having laterally spaced dependent side portions, a motor carried by said frame, power transmission means operatively connected to said motor, vertically slidable load carrying elements carried by the corners of said frame, fulcrumed levers engaged at one end with said load carrying elements, respectively, the other ends of said fulcrumed levers being connected to said power transmission means, said levers terminating in circular knobs, and said load engaging elements and said block provided with boxings engaged thereby, said boxings being of substantially larger size than said circular knob-like ends to provide a substantial degree of play in said connections.

11. In a lumber carrier of the character described, a load straddling frame having laterally spaced dependent side portions, said side portions comprising two longitudinally arranged members spaced apart a substantial distance, a motor carried by said frame, power transmission means operatively connected to said motor, vertically slidable load carrying elements carried by the corners of said frame, fulcrumed levers engaged at one end with said load carrying elements, respectively, pivots for said levers carried by one of said longitudinal members, tension tying members connecting each pivot to each of said longitudinal members, and the other ends of said fulcrumed levers being connected to said power transmission means.

ERNEST A. OETZEN.
